UNITED STATES PATENT OFFICE.

ABRAHAM SCHACHAT, OF BROOKLYN, NEW YORK, ASSIGNOR TO SLOCUM, AVRAM & SLOCUM, INC., OF NEW YORK, N. Y., A CORPORATION OF NEW YORK.

INTERNAL GRINDER.

1,250,107.

Specification of Letters Patent. Patented Dec. 11, 1917.

Application filed February 16, 1917. Serial No. 149,038.

To all whom it may concern:

Be it known that I, ABRAHAM SCHACHAT, a citizen of the United States, residing in Brooklyn, city of Greater New York, county 5 of Kings, State of New York, have invented certain new and useful Improvements in Internal Grinders; and I do hereby declare the following to be a full, clear, and exact description of the invention, such as will 10 enable others skilled in the art to which it appertains to make and use the same.

My invention relates to internal grinders, adapted more particularly for use in connection with bench-lathes, and has for its 15 objects, first, to provide an improved bearing for the shaft of the grinding-tool; secondly, so to construct the device that the shaft and its bearings may be swung away from their operative position, whereby the 20 work may be inspected without disturbing the adjustment; and thirdly, to provide a vernier reading whereby the adjustment of the tool in a horizontal plane may be determined with great accuracy.

25 These objects I accomplish in the manner and by the means hereinafter described and claimed, reference being had to the accompanying drawings, in which:—

Figure 1 is a horizontal sectional view of 30 my improved machine, taken through the center of the bearings for the shaft;

Fig. 2 is a side elevation of the machine; and

Fig. 3 is a vertical transverse sectional 35 view taken on the line III—III, Fig. 1, showing the same applied to a bench-lathe, the latter also being shown in section.

Similar numerals of reference denote corresponding parts in the several views.

40 In the said drawings, the reference numeral 1 denotes the base of the machine, the same being adapted to rest upon the upper surface of a lathe cross-slide 2, and being provided with the usual headed bolt 3, which 45 engages in the tool-post slot of the cross-slide, whereby the two are connected. It will be observed, with reference more particularly to Fig. 3, that the bolt 3 is mounted to be adjusted vertically by an eccentric 50 shaft 4 adapted to be operated by a handle 5, whereby said bolt 3 may be raised or low-

ered to clamp or unclamp it with respect to the cross-slide 2, in a manner readily understood. The upper face of the base 1 is provided with a central circularly raised portion 6 grooved in its outer face at 7, and over which fits a top-plate 8, the latter being circular in contour to conform to the base 1, as shown. Passing through the side of the top-plate 8, and in screw-threaded engagement therewith, is a screw 9, provided with a handle 10, adapted to engage the groove 7 in the base 1, not only to retain the two 55 against separation, but also, when screwed tightly to position, to retain the top-plate 65 against rotation on the base 1. Mounted in a pair of upstanding lugs 11 on the top-plate 8 is a horizontal shaft 12 which retains between the lugs 11, the extension 13 of a bracket 14, the latter being extended angularly and horizontally at 15 to provide separated supports for the bearings about to be described. Each of said extensions 15 terminates in a collar 16 adapted to receive therein an outer bushing 17 coned on its 75 inner face, which is adapted to fit over a similarly coned inner bushing 18, the latter being screw-threaded at its smaller end to receive the lock-nuts 19, whereby said bushing 17 will be retained thereon. Said inner 80 bushing 18 is provided with a screw 20 passing therethrough and adapted to engage a longitudinal groove 21 in the grinding-wheel carrying spindle 22 of the machine to retain said bushings rigidly in adjusted position. Said spindle 22 is provided with the usual handle 23 at one end, has detachably mounted thereon at the other end a suitable internal grinding-wheel 24, and at its center has fixed thereto a drive-wheel or pulley 25. 90 It will be understood that said spindle is capable of longitudinal movement in its bearings, but that the inner bushings 18 necessarily will revolve therewith, due to the engagement of the screw 20 with the groove 95 21 in said spindle, the two forming a splined engagement. The bushings 17 and 18 and their parts are protected suitably by removable dust-caps 26.

The bracket 14 carrying the spindle 22 100 and its parts is capable of being rotated on the shaft 12 from a horizontal to any ad-

justed position, and its movement toward the top-plate 8 when approaching the grinding position of the spindle may be regulated by the set-screws 27, in a well-known manner. And said bracket will be retained in its operative position by means of a bolt 28 pivoted at 29 to the top-plate 8 and adapted to be swung into a groove 30 in the extension 13 where it may be clamped by means 10 of a clamping-nut 31, in a manner readily understood. The extensions 15 of the bracket 14 are provided with oil-ducts or grooves 31 normally closed by dust-caps 32, said grooves leading to the bushings 18, and 15 through which oil passes by apertures 33 to provide the necessary lubricant. The base 1 is provided on its outer surface with a vernier reading 34, best seen in Fig. 2, which, in connection with an indicating 20 mark 35 on the top-plate 8, provides a means for determining the accurate adjustment of 25 said top-plate.

In operation, the base 1 is adjusted upon the tool-lathe so that the T-head of the bolt 25 3 is disposed in the tool-post slot of the cross-slide 2, and is clamped in position by rotating the cam-shaft 4. The top-plate 8 then can be adjusted circularly by loosening the screw 9 and rotating said top-plate upon the 30 base 1, the vernier scale 34 and its indicating mark 35 affording means for effecting a most accurate adjustment, which when attained may be maintained by locking the two parts together through said screw 9. The spindle 35 22 carrying the grinding-wheel 24 then may be adjusted vertically to the exact position desired by means of the set-screws 27 in a manner readily understood, and the parts may be locked in this position by engaging 40 the bolt 28 in the groove 30 of extension 13 and clamping the same in position by means of the nut 31. The tool is ready for operation, and the spindle 22, which is driven in the usual manner through power applied to 45 the wheel or pulley 25, may be shifted longitudinally by means of the handle 23, and while being rotated will be rotated with it the inner coned bushings 18, which are splined thereto, and which rotate within the 50 outer bushings 17 carried by the sleeves 16. When it is desired to inspect the work, the spindle 22 and its grinding wheel 24 may be withdrawn longitudinally from operative position, and said spindle and its carrying 55 bracket 13 may be rotated on the shaft 12 completely out of the way so as to permit an inspection of the work, as well as a ready gaging of the same. It will be appreciated that this movement of the grinding-wheel 60 and its spindle away from the work will in no way affect the adjustment of the tool, as it may be returned most accurately to its exact initial position.

Having thus described my invention, what

I claim as new and desire to secure by Let- 65 ters Patent is:—

1. In a grinding machine, an inclosing collar, a grinding-wheel carrying-spindle therein, an inner coned bushing splined to said spindle, an outer coned bushing fitting 70 over said inner bushing and within said inclosing collar, and a lock nut threaded onto the small end of the inner coned bushing to lock the two bushings together.

2. In a grinding machine, a base adapted 75 to be clamped to a lathe, and a tool-spindle supported by said base and mounted so as to be shifted on an axis parallel with its length bodily to and from its line of operation without disturbing the adjustment of 80 the same, said spindle also being shiftable in its bearings on its axial line.

3. In a grinding machine, a base adapted to be clamped to a lathe, and a tool-spindle mounted on horizontal pivots on said base 85 whereby it may be shifted on an axis parallel with its length bodily to and from its lines of operation without disturbing the adjustment of the same, said spindle also being 90 shiftable in its bearings on its axial lines. 95

4. In a grinding machine, a base adapted to be clamped to a lathe, a top-plate pivoted on said base, and a tool-spindle mounted on horizontal pivots on said top-plate in such a manner as to be capable of being shifted 100 on an axis parallel with its length bodily to and from its line of operation without disturbing the adjustment of the same, said spindle also being shiftable in its bearings on its axial line.

5. In a grinding machine, a base adapted to be clamped to a lathe and having a central circular raised portion, said raised portion being grooved annularly in its side face, a top-plate recessed to fit over said raised 105 portion, a tool-spindle carried by said top-plate, and a screw passing through said top-plate and adapted to engage the groove in said raised portion to lock said base and top-plate in any adjusted position. 110

6. In a grinding machine, a base adapted to be clamped to a lathe, a bracket supported on a horizontal pivot on said base, a tool-carrying-spindle carried by said bracket, adjustable means for limiting the movement of 115 said bracket with respect to said base, and means for locking said bracket when adjusted with respect to said base.

7. In a grinding machine, a base adapted 120 to be clamped to a lathe, a top-plate mounted to be rotated upon said base, a bracket supported upon a horizontal pivot on said top-plate, a tool-carrying-spindle carried by said bracket, adjustable means for limiting the movement of said bracket with respect to said top-plate, and means for locking said bracket when adjusted with respect to 125 said top-plate.

8. In a grinding machine, a base adapted to be clamped to a lathe, a top-plate mounted to be rotated upon said base, a bracket mounted on a horizontal pivot on said top-plate, a tool-carrying-spindle carried by said top-plate, set-screws in said bracket adapted to regulate the distance between the free end of said bracket and said top-plate, a pivoted screw on said top-plate adapted to be swung into a slot in said bracket, and a nut for **10** clamping said screw to lock said bracket to said top-plate.
- 5 In testimony whereof, I have hereunto set my hand this 14th day of February, 1917.

ABRAHAM SCHACHAT.
